UNITED STATES PATENT OFFICE.

ORSON W. BRENIZER, OF PHILADELPHIA, PENNSYLVANIA, ASSIGNOR OF ONE-FIFTH
TO ANDREW V. GROUPE, OF PHILADELPHIA, PENNSYLVANIA.

CABLE-SUPPORT.

1,373,166.

Specification of Letters Patent. Patented Mar. 29, 1921.

Application filed December 29, 1920. Serial No. 433,758.

To all whom it may concern:

Be it known that I, ORSON W. BRENIZER, a citizen of the United States, residing at Philadelphia, in the county of Philadelphia and State of Pennsylvania, have invented certain new and useful Improvements in Cable-Supports, of which the following is a specification.

This invention relates to improvements in cable supports adapted to be hung at intervals upon a supporting or messenger wire to receive and support a cable therein, the messenger wire being formed of a plurality of strands twisted around a central or core strand and providing the messenger wire with relatively large and small diameters in alternate succession, forming intermediate shoulder portions.

The object of the invention is to provide a cable support of novel, simple and efficient construction which may be formed of a single piece of spring wire and having provision: first, whereby shoulder portions of the messenger wire may be utilized to prevent displacement of the cable support longitudinally thereof, in a construction employing hooks to attach the support to the messenger wire, without requiring a spring pressed gripping of the hooks against the messenger wire to prevent the hooks from leaving it while a cable is being drawn through the support; second, whereby the cable support may be constructed of a relatively short length of wire and possess many advantages not possessed by prior constructions which do not require a greater length of wire, thereby resulting in a great saving of material; and, third, whereby many advantageous results are attained.

The invention consists in the novel construction, combination and arrangement of parts hereinafter described and claimed.

In the accompanying drawings, illustrating my invention,

Figure 1 is a transverse section through a supporting or messenger wire having a cable support applied thereto embodying my invention.

Fig. 2 is a side view thereof.

Fig. 3 is a top view thereof.

Figs. 4 and 5 are enlarged, transverse sections of the messenger wire, on lines 4—4 and 5—5, respectively, of Fig. 2, showing the two cable hanger hooks applied thereto.

Fig. 6 is an enlarged transverse section 55 of the messenger wire.

Referring to the drawings, 2 designates the supporting or messenger wire which comprises a central or core strand 3 and six outer strands 6 lying side by side and twisted in spiral form around the core strand 3, as clearly shown in the drawings. A messenger wire of this character has relatively large and small diameters, which occur in alternate succession longitudinally of the wire, as indicated at 7 and 8, respectively, in Fig. 2, and which extend continuously, in spiral form around the wire 2 from end to end thereof, following the lines of its twisted strands 6. These alternating large 70 and small diameters are also indicated at 7 and 8, in Fig. 6, where it will be observed that each of two parallel lines which touch opposite sides of the wire 2 at one of the small diameters 8 thereof also touch two of 75 its twisted strands 6.

The cable support is formed of a single piece of spring metal, and it comprises a cable-receiving loop 9 extending beneath the supporting or messenger wire 2, hooks 10 80 and 11 formed on the respective end portions of the loop 9 and an arm 12 formed on and extending from the hook 10.

The hooks 10 and 11 are hooked around and over the supporting wire 2 from opposite sides thereof to connect the cable support thereto in a manner to permit it to act as a support for suspending a cable, indicated at 13 in Figs. 1 and 2, from the supporting wire 2.

The oppositely disposed faces 14 and 15 of the hooks 10 and 11, respectively, extend parallel to each other, and the distance between the faces 14 of the hook 10 and the faces 15 of the hook 11 are each less than 95 the large diameter 7 of the supporting wire 2 and but slightly in excess of or substantially equal to the small diameter 8 of the supporting wire, for a purpose hereinafter described.

The loop 9 extends transversely of the supporting wire 2 for the reception of the cable 13, and the side arms of the loop 9 diverge from the bottom of the loop longitudinally of the supporting wire 2 to space 105 the hooks 10 and 11 and permit each to be hooked around and over the supporting wire 2 at one of the small diameters thereof.

spaced from the other, as clearly shown in the drawings. The hooks 10 and 11 are set in parallel relationship and to extend at right angles to the supporting wire 2, and 5 the distance between the centers of the hooks 10 and 11, both before and after the cable support is applied to the wire 2, is equal to the distance between the two spaced small diameters 8 of the supporting wire 2 10 which receive the hooks.

The arm 12 extends from the hook 10 in the direction of the length of the wire 2 and away from the hook 11, and its free end extends downwardly below the plane of the 15 top of the supporting wire 2 to engage the same on the opposite side thereof to the side occupied by the curved body portion of the hook 10, for a purpose presently appearing.

The relation of the parts of the cable 20 support to each other, before and after the support is applied to the supporting wire 2, is the same or substantially the same as shown in the drawings; and, in applying the support to the wire, the hook 10 is first 25 applied to the wire 2 at one of its small diameters 8. In applying the hook 10 to the wire 2, the cable support is turned and manipulated to pass the arm 12 over the wire 2 in advance of the hook 10, and, there- 30 after, the hook 10 is engaged with the wire 2. The hook 10 fits the wire 2 sufficiently loose to allow it to be rocked enough to permit the hook 11 to move under the wire 2 while the hook 10 is being applied thereto.

35 After the hook 10 has been applied to the wire 2, the hook 11 is moved beneath the wire 2 in the direction of the arrow 14 by springing the loop or body 9 of the support until the free end of the hook 11 clears the 40 side of the wire 2 on which the arrow 14 is located; whereupon the hook 11 is raised and engaged with the wire 2, as illustrated 45 in the drawings, while the loop or body portion 9 of the support is permitted to spring back to or toward its normal condition. When the hook 11 is thus applied to the 50 wire 2, the loop 9 is sprung in opposition to pressure of the hook 10, in the direction of the arrow 15, against the wire 2 and in opposition to pressure of the free end of the arm 12, in the direction of the arrow 16, 55 against the wire 2.

The cable support may be removed from the wire 2, when desired, by a reversal of 55 the operation just described for its application thereto.

It will now be understood that, when the cable support is applied to the supporting wire 2 therefor, and a cable is drawn through 60 the loop 9 in either direction, the arm 12 engaging one side of the wire 2 will prevent the hook 10 from being accidentally disengaged from or leaving the wire 2 while the hook 11 is engaged therewith, and that

the hook 10 and arm 12 will cooperate to 65 prevent the hook 11 from being accidentally disengaged from the wire 2, by requiring the loop 9 to be sprung from the condition shown in the drawings for such disengagement.

When a cable is drawn through the loop 70 9 of the support, in either direction, the hooks 10 and 11 will engage the shoulders formed between the large and small diameters 7 and 8, respectively, of the supporting 75 or messenger wire 2 and thereby prevent the cable support from being displaced longitudinally of the wire 2 during the cable drawing operation.

Of course, the normal condition of the 80 cable support, before it is applied to the supporting wire 2, may be such that, in applying it to the wire 2, it will be necessary to spring the loop 9 to such an extent that the hook 10 and arm 12 will continue to exert 85 pressure against the wire 2 in the directions of the arrows 15 and 16, respectively, and that the hook 11 will exert pressure against the wire 2 in the direction of the arrow 17, after the application of the cable support 90 to the wire, but such pressure is not necessary either to prevent the accidental disengagement of the hooks 10 and 11 from the wire 2 or to prevent the displacement of the cable support longitudinally of the wire 2 95 when a cable is drawn through the loop 9 in either direction.

I claim as my invention:

The combination with a supporting wire 100 having relatively large and small diameters in alternate succession, of a cable support comprising a cable receiving loop extending beneath the supporting wire, a hook on one end portion of said loop engaged with said wire, and a hook on the other end portion 105 of said loop and engaged with said wire and extending around one side thereof and having an arm extending therefrom in the direction of the length of said wire and adapted to engage the opposite side thereof to 110 prevent the accidental disengagement of said hooks from the supporting wire, each of said hooks engaging the top and bottom 115 of the supporting wire, one of said hooks having two opposing faces adjacent to two opposite sides of the supporting wire at one of its small diameters, the distance between said faces being less than the adjacent large diameter of the supporting wire, whereby displacement of the cable support longitudinally of the supporting wire is prevented, without the aid of any spring, pressed gripping action of the cable support upon the supporting wire.

In testimony whereof I affix my signature 125 hereto.

ORSON W. BRENIZER,
